UNITED STATES PATENT OFFICE.

DANIEL KABER, OF CLEVELAND, OHIO.

TRANSFER-SIGN.

1,299,353.

Specification of Letters Patent.

Patented Apr. 1, 1919.

Application filed August 2, 1915. Serial No. 43,104.

To all whom it may concern:

Be it known that I, DANIEL KABER, a citizen of United States, residing at Cleveland, in the county of Cuyahoga and State of Ohio, 5 have invented certain new and useful Improvements in Transfer-Signs, of which the following is a specification.

This invention relates to a paper transfer sign and it comprises a backing sheet having 10 a coating of adhesive material adapted to temporarily hold the sign characters which are provided upon their outer faces with a coating of adhesive material, by means of which they may be transferred to glass or 15 other material.

The invention may be further briefly summarized as consisting in the construction and combination of parts hereinafter set forth in the following description, drawings 20 and claims.

Referring to the drawings, Figure 1 is a front elevation of a sign, arranged according to my invention; Fig. 2 is a view showing a piece of glass with the sign in the 25 process of application; Fig. 3 is a sectional view of the piece of glass showing the sign applied with the packing sheet partially removed, and also showing the several layers of material, but omitting the embossing of 30 the backing sheet, which would be imperceptible on the scale of this view; Fig. 4 is an enlarged view showing a portion of a sheet of embossed paper used in a modified form of the invention, and Fig. 5 is a sectional view of a portion of a sheet of the 35 same embossed paper showing the characters applied.

In the drawings 1 represents a portion of a window pane, or a piece of any transparent material such as glass.

The sign comprises a temporary backing sheet 2 of embossed paper or other material having upon the face thereof a coating 3 of adhesive material adapted to temporarily hold in place suitable sign characters 4. The 45 embossing is shown on a magnified scale in Fig. 5, the paper being pressed or rolled in dies to form successive prominences and valleys or depressions, as will be readily understood. The adhesive 3 is, of course, applied 50 to the entire surface of the embossed sheet but it does not take such a good hold of the sign characters at the valleys or depressions as it does at the prominences. The sign characters therefore may be peeled off 55 more readily from the embossed sheet than from a backing sheet having a continuous smooth surface. Each of the sign characters is provided, upon its outer face, with a coating 5 of adhesive material adapted to ad- 60 here to glass or other transparent material, or to hold sufficiently so that the temporary backing sheet may be removed thus leaving the sign characters applied to the glass or 65 other material.

Having described my invention, I claim:—

A paper sign, comprising a backing sheet of embossed paper, paper sign characters temporarily secured to said embossed sheet by a layer of adhesive material lying between the sign characters and the embossed sheet, and a coating of adhesive material upon the exposed face of the sign characters. 70

In testimony whereof I affix my signature in presence of two witnesses as follows:

DANIEL KABER.
